UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed May 29, 1922. Serial No. 564,431.

To all whom it may concern:

Be it known that I, RAYMOND A. HEISING, a citizen of the United States, residing at Millburn, in the county of Essex, State of New Jersey, have invented certain new and useful Improvements in Telegraph Systems, of which the following is a full, clear, concise, and exact description.

This invention relates to telegraph systems and more particularly to a multiplex high speed telegraph system.

It is an object of the invention to provide a multiplex telegraph system which can be operated at high speed and which is particularly suitable for operation by radio.

It is another object of the invention to provide a synchronizing means operable with such a high speed system.

To accomplish these objects and in accordance with a feature of the invention, there is provided a system in which telegraph signals are detected at high speed stored and then transferred at a lower speed to other receiving mechanisms such, for example, as a printing mechanism of the type in common use in multiplex telegraph systems. In accordance with another feature of the invention a synchronizing method is provided which determines the position of the transferring mechanism with respect to the receiving mechanism at the beginning of the transfer of each series of impulses representing a character.

These and other features of the invention will be more clearly understood by reference to the accompanying drawings in which Fig. 1 is a diagrammatic view of the storing and transferring apparatus embodying features of this invention and arranged for radio receiving; Fig. 2 is a schematic view of a portion of the mechanism shown in Fig. 1; Fig. 3 is a sectional view taken along the line 4—4 of Fig. 2; and Fig. 4 is an end view of the mechanism shown in Fig. 3 with portions cut away to more clearly show the gearing mechanism.

Referring now more particularly to Fig. 1, there is disclosed a radio detecting outfit comprising antenna 5, transformer 6 and detector 7 together with a grid leak 8 and variable condenser 9. The impulses received by this outfit are transmitted to an electromagnet 10 which is adapted to record magnetically the respective impulses upon

an endless telephone wire 11 driven by 55 means of the wheel 12 which is directly connected to a constant speed motor 13. This telephone wire also passes over a wheel 14 which is connected to the mechanism in a manner more clearly shown in Figs. 2, 3 60 and 4, the detail construction of which will be explained hereinafter. The system illustrated employs nine channels for the transferring mechanism, thus permitting the transfer of signals received at a frequency 65 of three or four hundred cycles, but the device is not limited to such velocities since it may be arranged to employ from 40 to 50 channels, in which case the storing may be at approximately 1200 to 1500 cycles 70 while the relative motion of the magnets to the wire in any case would be such as to provide a speed of operation of 30 to 40 cycles, a frequency which is very easily adapted to operate the printing mechanism 75 of the present telegraph systems. The wheel 14 is arranged to carry 18 pairs of electromagnets, each pair of magnets having its windings connected in series and the core portions disposed on opposite sides of 80 and in close proximity to the telephone wire. The electromagnet pairs 15 to 32 inclusive, are rotated in the same direction as the telephone wire but at substantially nine-tenths the speed of the latter so that 85 the space taken up on the wire 11 by a set of impulses passes an electromagnet during the time occupied by approximately a half revolution of the wheel 14. Each pair of receiving magnets 15 to 32 is provided with 90 a brush member 35 adapted to contact during its operating period with one of the contact segments 36 to 44. These segments are connected to separate circuits for operating a printing or similar recording mechanism. For the sake of clearness, only the circuit arrangement connected to segment 95 36 is shown, this circuit arrangement consisting of an integrator 37, amplifier 38 and relay 39.

Referring more particularly to Figs. 2, 3 and 4, the wheel 14 is provided at its periphery with a groove to receive the telephone wire 11, thus rotating the wheel 14 on the shaft 45. Wheel 14 is also provided 105 with an inner gear 46 which engages a pinion 47 rigidly connected to a shaft 48 which, in turn, is journaled in plate 49, this

plate being free to rotate on the shaft 45. A pinion 50 secured at the opposite end of shaft 48 is adapted to engage the teeth of an inner gear on the wheel 51 carrying one of each pair of the magnets 15 to 32. This wheel is secured rigidly to the shaft by means of a set screw 53 and a second magnet carrying wheel 54 carrying the remaining magnets is also rigidly secured to the shaft by means of a set screw 55. The plate 49 is provided at its periphery with gear teeth which are adapted to mesh with pinion 56 connected on the shaft 57 and journaled in the wheel 51. The other end of shaft 57 is provided with a pinion 58 which meshes with the gear 59 adapted to rotate freely about the shaft 45 and which is connected by means of worm gearing 61 to a motor 62. Rigidly connected to the magnet carrying wheel 54 is a brush plate 65 containing suitable brushes 35-35 which are adapted during a portion of each revolution to engage corresponding contact segments 36 to 44. The contact segments are mounted upon a stationary insulating plate 66 which is shown mounted on the bearing support 67. The brush plate 65 also carries on its outer circumference, a brush 68 which is adapted to engage a contact segment 69 and a brush 70 adapted to engage contact segments 71 and 72. Connected to contact segment 69 is an electromagnet 73 as shown in Fig. 1, which has its core portion in close proximity to the telephone wire. The segment 71 is connected in circuit with an integrating network 74, amplifier 75 and relay 76, and the contact segment 72 is connected in a corresponding manner to an integrating network 77, amplifier 78 and relay 79. The local contacts of relays 76 and 79 are connected, as shown, to the windings of a motor 62 to permit synchronizing the system in a manner to be explained hereinafter. In order to permit the continuous transfer of signals, a wiping magnet 81 is arranged with its core portion in close proximity to the telephone wire and adapted to wipe off the message after it has been transferred to the local circuits.

In the operation of the device, a series of impulses are transmitted either by wire or by radio employing a transmitting mechanism which may preferably be of the general type disclosed in my copending application, Serial No. 217,139 filed February 14, 1918, issued as Patent No. 1,426,733, Aug. 22, 1922. In the arrangement shown, which is adapted for radio operation, the impulses are received by the antenna 5, and the detector 7 and then by means of the magnet 10 are stored magnetically upon the telephone wire 11. As the magnets 15 rotating in a counterclockwise direction approach the position shown, their corresponding brush 35 engages contact segment 36 which is connect-

ed by means of a local circuit to a relay 39 in a standard printing mechanism such, for example, as disclosed in Patent No. 1,201,809 of October 17, 1916 to A. F. Dixon. At this instant, the parts are so synchronized that a series of impulses representing a character are stored on that portion of the telephone wire located between magnets 15 and magnets 32 and the magnets 15 start to transfer the message to the local circuit. 75

Since the wheel 14, upon which the magnets are mounted, revolves at substantially nine-tenths the speed of the telephone wire, the message will be taken up at a speed corresponding to the difference in speed of the magnets and the telephone wire so that by the time magnets 15 reach the position shown as being occupied by magnets 24, the portion of the telephone wire which at the beginning of the message was positioned between magnets 15 and 32 now is located in the position shown between magnets 24 and magnets 25 and the brush is just passing off from the contact segment 36 thereby disconnecting the local circuit of that channel. At approximately that time, brush 35 for magnets 32 will have reached the position shown for magnets 15 thus connecting magnets 32 with contact segment 44 which will transfer the message on the next section of the telephone wire to a local printing circuit corresponding to that shown for contact segment 36. As the wheel 14 is rotated the segments for the various channels are connected to the corresponding magnets and as the telephone wire passes the wiping magnet 81 the message is wiped off and the wire placed in condition to receive a message as it again passes under magnet 10. 100

In order to properly synchronize the mechanism so that each channel transfers one set and only one set of impulses, it is necessary to insure that a pair of magnets reach the position shown by magnets 15, the telephone wire located between magnets 15 and 32 has stored upon it a complete set of impulses representing a character which is to be transferred to magnets 15 by the time they reach the position shown by magnets 24. To accomplish this, it is necessary, in the first place, that the transmitting mechanism be driven at approximately the speed of the receiving telephone wire and it is possible commercially to obtain motors which will operate within 1 per cent of constant. Each set of impulses represents a character and consists of two synchronizing impulses or phase adjusting signals and five printing signals preferably following the Baudot code, such as used in various printing telegraph systems. The phase adjusting signal consists of a space and a dot. As one of these characters passes under the synchronizing magnet 73, a pulse is produced in one direction. The synchronizing 115 120 125 130

- magnet and the brushes 68 and 70 are so placed with respect to the wheel 14 and the electromagnet 15 that the shifting of the wheel 14 by the phase shifting mechanism 5 to be described later will always cause the magnets to arrive at the point shown by magnets 15 just as the beginning of each character arrives there. The phase shifting is produced by means of the brush 68 making contact with the segment 69 or brush 70 making contact with either contact 71 or 10 72. If the parts are in perfect synchronism, the brush 70 will be at the point shown, midway between contact 71 and contact 72, 15 when the synchronizing impulse is picked up by electromagnet 73, in which case no correction need be applied to the mechanism. If, however, the brush 70 is traveling at a slightly different speed than the telegraph 20 phone wire, it will be in engagement with either contact 71 or contact 72 when the synchronizing impulses pass synchronizing magnet 73. In case the brush is on contact 71, an impulse will be transmitted from electromagnet 73 through brush 68, brush 70, contact 71, integrator 74, amplifier 75, and relay 76. The energization of the high speed relay 76 causes the closing of a local circuit including the winding of motor 62 25 and battery 80, thereby causing the rotation of gear 59 and in turn, the rotation of plate 69 in a direction to shift the magnet carrying wheels 51 and 54 in a forward direction. On the other hand, if the speed of the telegraph 30 wire is such that brush 70 is in engagement with contact segment 72 at this instant, a circuit is closed through synchronizing magnet 73, contact 69, brushes 68 and 70, contact 72, integrator network 77, amplifier 35 78 and relay 79. Upon the energization of relay 79, a local circuit is closed containing the other half of the winding of motor 62 and the battery 80. The motor 62 is then rotated in the opposite direction and by 40 means of worm drive 61 and gears 59 and 49 causes the magnet carrying wheels 51 and 54 to be shifted in a backward direction. While in the arrangement illustrated means 45 is shown for synchronizing only once in revolution of the magnet carrying wheels, it is obvious that by employing additional brushes and contact segments corresponding to segments 71 and 72 the device may be synchronized for each set of impulses transmitted. 50
- What is claimed is:
1. A telegraph system comprising means for detecting impulses at high speed, means for storing such impulses, means for transferring the impulses to the local circuits at a speed relatively lower than the speed at which the impulses are stored, and means for synchronizing the speed of the transferring means with the speed of storing the impulses on said storing means, and means 55 in the local circuits for making a record of the impulses received.
  2. A telegraph system comprising means for detecting impulses, means for magnetically storing said impulses on a continuously moving telephone wire, means for transferring the impulses at a speed to local circuits invariably slower than said detecting means, and means in the local circuits for making a printed record of the impulses received. 60
  3. A telegraph system comprising means for detecting impulses of high frequency, means for storing the impulses detected on a continuously moving telephone wire, means for transferring signals from the telephone wire to local circuits at a low frequency, and means for synchronizing the speed of the transferring mechanism with the speed of storing of signals on the telephone wire. 65
  4. In a multiplex telegraph system, a transferring mechanism cooperating with a continuously moving telephone wire to transfer signals stored at high speed to local circuits at a speed relatively lower rate than the signals are stored, said mechanism comprising a plurality of transfer magnets moving in operative relation to the telephone wire but at a slightly different speed. 70
  5. In a multiplex telegraph system employing a plurality of channels, a transferring mechanism cooperating with a continuously moving telephone wire and local circuits for the transfer of signals stored on the telephone wire at high speed to the local circuits at a low speed, said mechanism including a plurality of stationary channel bars each of said bars 75 being connected to a local printing circuit, a plurality of electromagnets moving in operative relation to the telephone wire and at a speed differing a fixed ratio therefrom, and means for synchronizing the movement of the electromagnets with the spacing of signals on the telephone wire. 80
  6. In a multiplex telegraph system, a receiving device operative to receive signals transmitted at a high speed, a storing device associated with said receiving device for storing the impulses of a plurality of channels, a recording instrument for each of the channels, operative at a relatively lower speed than said receiving device, and means for transferring the impulses stored in said storing device to the recording instrument of the respective channels. 85
  7. In a multiplex telegraph system including a transferring mechanism cooperating with a continuously moving telephone wire and local circuits for the transfer of signals stored in the telephone wire at a high speed to the local circuits at a low speed, a synchronizing 90

electromagnet mounted in operative relation to the telephone wire, a motor adapted to shift the position of the transferring mechanism with respect to the telephone wire, and means for operating said motor in either direction dependent upon the synchronism of the system.

8. In a multiplex telegraph system, means for detecting multiplex telegraph signals at high frequency, means for storing said signals on a continuously moving telephone wire, a grooved gear wheel about which the telephone wire rotates, a shaft upon which said wheel rotates freely, a pair of wheels rigidly secured to said shaft each supporting a plurality of electromagnets having their core portions in operative relation to the telephone wire, means for rotating said wheels at a

fixed speed relation with the grooved gear 20 wheel, and means for altering the speed dependent upon the spacing of impulses stored on the telephone wire.

9. In a multiplex telegraph system, a receiving device operative to receive signals 25 transmitted at a high speed, a continuously moving wire for storing the impulses of a plurality of channels, a recording instrument for each of the channels operative at a relatively lower speed than said receiving 30 device, and means for transferring the impulses stored in said moving wire to the recording instruments of the respective channels.

In witness whereof, I hereunto subscribe 35 my name this 22nd day of May A. D., 1922.

RAYMOND A. HEISING.
